UNITED STATES PATENT OFFICE.

PERCY M. BACHELDER, OF WORCESTER, MASSACHUSETTS.

LOOSE-CARD BILL HOLDER.

Application filed July 27, 1922. Serial No. 577,912.

To all whom it may concern:

Be it known that I, PERCY M. BACHELDER, a citizen of the United States, and resident of Worcester, in the county of Worcester 5 and State of Massachusetts, have invented certain new and useful Improvements in Loose-Card Bill Holders, of which the following is a specification.

It is the practice in some large business 10 concerns to bill their "charged" customers once a month, retaining a carbon copy of each bill sent out. Each unpaid bill, as indicated by the carbon copy of the bill sent to the customer, is debited to the respective 15 customer in a ledger. When the bill is paid the account is credited thus balancing the account. The ledger is usually a loose-leaf scheme, but notwithstanding the advantage of using a loose leaf ledger, there is the disadvantage 20 of having to examine the paid or balanced accounts when drawing off a statement of the unpaid bills.

The main object of this invention is to provide a loose card bill holder adapted to 25 receive and hold in an upright position the carbon copies of the bills sent out to customers, so that these bill holders with the bills therein may be arranged in a card index box and constitute a ledger of unpaid 30 accounts. The bill holder is preferably formed with an opening arranged in the manner of the opening in the so-called window envelope, so that the name and address 35 of the customer written on the bill will be visible on the face of the bill holder without the necessity of making any entry on the bill holder. This arrangement permits of the removal of the bill when paid and the re-use of the bill holder.

Another object of the invention is to provide a loose-leaf bill holder with tabs which 40 may be turned up to be readily visible and on which may be written words of caution, such as "Watch," "Stop credit" or other 45 words to indicate the customer's rating or standing.

In the drawing:

Fig. 1 is a face view of the upper part 50 of a loose-leaf bill holder with a bill therein and one of the caution tabs turned up;

Fig. 2 a vertical sectional view on the line 2-2 of Fig. 1; and

Fig. 3 a face view of the bill holder complete with slight modifications.

Referring to the various parts by numer-

als, 1 designates the body of the bill holder which is preferably made of light card board or stiff paper of sufficient strength and stiffness to stand up in a card index box. A pocket 2 is formed across the upper end 60 of the body part of the holder. This pocket extends downwardly over the body 1 a suitable distance and its lower end is open so that the upper part of a sheet 3 may be slipped up into it. The sheet 3 represents 65 a carbon copy of a bill sent to a customer. The pocket 2 may be formed by turning down, or folding over, a part of the body 1 of the holder to form the front wall 4 of the pocket. The vertical edges of the pocket 70 wall 4 may be secured to the corresponding edges of the body in any suitable manner in order to complete the pocket; the lower edge of said wall 4 being free so that the lower end of the pocket will be open. In 75 Fig. 1 the vertical edges of the wall 4 are secured by clips 5; and in Fig. 3 the edges are shown as secured by lines of stitches 6, and by lines of paste or glue. The pasted or glued lines are indicated by dotted lines 80 7. As shown in the drawing the wall 4 is formed by folding over the upper end of the body part 1. It will, of course, be understood that the wall 4 may be made of a separate piece secured in place on the 85 body 1.

In the wall 4 is formed an opening 8 properly positioned and of a suitable size to display the name of the customer when the copy of the bill is properly inserted in 90 the pocket 2.

Vertical lines 9 of perforations extend from the upper margin of the opening 8 to the upper edge of the wall 4. These lines of perforations form caution tabs 10. By 95 tearing the wall 4 along the lines 9, the tabs may be turned up, as shown in Fig. 1, and the words printed on the inner sides of them displayed. If desired the words of caution may be written on the tabs after they have 100 been separated along the lines of perforations. It is manifest that when these tabs are turned up they will be displayed above the upper edges of the bill holders in a card index box, and the accounts requiring 105 special treatment and caution may be readily and quickly distinguished from the other unpaid bills.

While the caution tabs are shown as formed by lines of perforations in the wall 110

4 of the pocket, it is clear that they may be otherwise formed.

In the use of the loose card bill holder described herein, the carbon copy of the bill sent to a customer is inserted in the pocket 2 of a bill holder with the name of the customer visible through the opening 8. The bill holder is then placed in a box with the pocket end up. The body 1 of the holder is 10 large enough to form a substantial backing for the copy of the bill. When the bill is paid, the holder is removed from the box of unpaid bills and the copy of the bill is removed from the holder. The bill is marked 15 paid and laid aside for entry in a ledger, or for any other disposition desired, and the holder reserved for further use. In this manner the unpaid accounts may be readily examined without the necessity of running 20 through the paid or balanced accounts. It is unnecessary to make entries in the ledger until the account is paid and there need be no unpaid accounts in the ledger.

Whenever desired one or more of the caution tabs may be turned up to indicate that an account requires special treatment.

The wall 4 is flat against the face of the body 1 and effectually holds the bill sheet in the pocket.

30 What I claim is:

1. A loose card bill holder comprising a body part, and a wall across the upper part of said body part and having its upper edge and its side edges connected to the said body 35 to form a pocket having an open lower end to permit the upper end of a sheet to be inserted in said pocket, the said wall being formed with an opening to permit the display of a name written on said sheet.

40 2. A loose card bill holder comprising a body part, and a wall across the upper part of said body and lying flat against it and having its upper edge and its side edges secured to said body to form a flat pocket having an open lower end and adapted to receive the upper end of a sheet, the said wall being formed with an opening to permit the display of a name written on said sheet.

45 3. A loose card bill holder comprising a body part, a wall across the upper part of said body part and having its upper edge and its side edges connected to said body part to form a pocket having an open lower end to permit the upper end of a sheet to be inserted in said pocket, the said wall being formed with an opening to permit the

display of a name written on said sheet, and caution tabs carried by the holder.

4. A loose card bill holder comprising a body part, a wall across the upper part of said body part and having its upper edge and its side edges connected to said body part to form a pocket having an open lower end to permit the upper end of a sheet to be inserted in said pocket, the said wall being 60 formed with an opening to permit the display of a name written on said sheet, and caution tabs carried by the holder and adapted to be turned up to display words written thereon.

5. A loose card bill holder comprising a body part, a wall across the upper part of said body part and having its upper edge and its side edges connected to said body part to form a pocket having an open lower 75 end to permit the upper end of a sheet to be inserted in said pocket, the said wall being formed with an opening to permit the display of a name written on said sheet, and caution tabs carried by the holder and adapted to be turned up above the upper edge of the holder.

6. A loose card bill holder comprising a body part, a wall across the upper part of said body part and forming a pocket having 80 an open lower end to permit the upper end of a sheet to be inserted in said pocket, the said wall being formed with an opening to permit the display of a name written on said sheet, and caution tabs formed by lines of 90 perforations in said wall and adapted to be turned up above the upper edge of the body part of the holder.

7. A loose card bill holder comprising a sheet of material, a pocket at the upper end 95 of said sheet, the said pocket being formed by folding over a portion of the upper end of the sheet and connecting the side edges of the folded-over portion to the main portion of the sheet, the said pocket being open 100 at its lower end to permit the upper end of a document to be inserted therein and the said folded-over portion being formed with an opening to permit the display of a name written on said document, and a caution tab 105 formed by lines of perforations in the folded-over portion and adapted to be turned up, the said lines of perforation extending from the said name-display opening.

In testimony whereof I hereunto affix my 110 signature.

PERCY M. BACHELDER.
